UNITED STATES PATENT OFFICE.

CHARLES DAWSON AND EDWARD E. MORGAN, OF BELVIDERE, ILLINOIS.

CARTRIDGE FUSE-PLUG.

1,314,576.

Specification of Letters Patent.

Patented Sept. 2, 1919.

Application filed May 4, 1918. Serial No. 232,582.

To all whom it may concern:

Be it known that we, CHARLES DAWSON and EDWARD E. MORGAN, citizens of the United States, and residents of Belvidere, Boone county, and State of Illinois, have invented certain new and useful Improvements in Cartridge Fuse-Plugs, of which the following is a specification.

Our invention relates to cartridge fuse plugs, and the object of our improvement is the provision of a simple and efficient fuse plug. A further object is the provision of a fuse plug which will utilize ordinary fuse wire such as comes in the market wound on spools and in which no tools are necessary for the adjustment of the fuse wire in the plug. A further object is the provision of a fuse plug in which the connection between the plug and its socket automatically binds the electrical connecting parts in the plug tightly together. Other objects will appear hereinafter.

An embodiment of our invention is shown in the accompanying drawing forming a part of this specification and in which—

Figure 1 is a side view with portions broken away to show underlying parts of our invention showing the same applied to a socket.

Fig. 2 is an enlarged perspective view of a cap used in the construction.

Fig. 3 is a perspective view of an electrical non-conducting member used in the fuse cartridge; and

Fig. 4 is an end view of the member shown in Fig. 3.

Referring more particularly to the drawing, we have shown the representation of a socket 5 of the Edison base type in dotted lines in Fig. 1, although other forms of socket may be used if desired. This form of socket is provided with a recess in one side with a threaded electrical conductor 6 around on the wall of said recess. At the center of the conductor 6 and insulated from the latter is a conductor 7.

Our fuse plug comprises an electrical non-conducting body member 8 which may be of porcelain or any other desired substance. The member 8 is provided with a bore 9 extending longitudinally in one end thereof and preferably throughout the greater part of its length. The inner end, marked 10 in Fig. 1, has threads formed on its periphery and on these threads is provided a thin annular sheet metal conductor

11. This conductor 11 is provided with threads adapted to fit tightly on the threads 10 of member 8. The connection between the conductor 11 and member 8 is such that when the plug is screwed in the conductor 6, the conductor will not be loosened or pulled off the end 10 of said member.

At one end of the conductor 11 is a narrow extension 12 which extends along the side of member 8 and through a perforation 13 into and across the bottom of recess 9. The member 12 provides a connection between the inner end of the cartridge, described later, and the conductor 11.

In the bore 9 we provide a fuse cartridge which preferably comprises an electrical non-conducting member 14 which may be of fiber or any other desired substance. The member 14 is preferably of a cross section corresponding to the cross section of bore 9 and provided with a groove 15 which extends across the end 16 and along one side of said member with the other end of the groove extending across the end 17 of said member and terminating in a longitudinal recess 18 in the end 17 of the member 14. The groove 15 and recess 18 are preferably formed in diameters so that fuse wires of desired diameters will substantially fill such recess and groove, and so that the caps 19 and 20 will form electrical contact with the end portions of the fuse wire 21. In fitting a fuse wire to the member 14, one end 22 is inserted in the recess 18 and the fuse wire 21 then bent and pressed into the groove 15 with the end 23 of the fuse wire terminating in the end of the groove 15 substantially as indicated in Fig. 1. The fuse wire being of a soft material, it may easily be broken off or even cut with the thumb nail at the end 23. After the fuse wire is brought to this position, caps 19 and 20 are slipped onto the ends of member 14 and over the end portions of the fuse wire 21. The arrangement of the parts is such that when the member 8 has its member 11 adjusted into the member 6 of the receptacle, that the connection between the members 6 and 11 will force the caps 19 and 20 tightly against the end portions of the fuse wire 21, thereby clamping the caps 19 and 20, fuse wire 21 and conducting members 7 and 12 tightly together, forming good electrical contact.

One of the caps 19 and 20, the one at the outer end of recess 9 which is shown in the drawings as being cap 19, is provided with a

flange 24 so that when the fuse plug is taken out of the socket 5, a thumb nail may be inserted under the flange 24 to pull the fuse cartridge out of the recess 9. The flange 24 may extend entirely around the base of the cap 19, or not all the way around if desired.

The caps 19 and 20 are preferably formed in diameters so that the fuse cartridge will slide easily in the recess 9. To prevent the fuse cartridge becoming misplaced in the recess 9 when the plug is not in the receptacle 5, we provide friction means on the fuse cartridge for holding the latter in the recess 9. In the form shown we have provided spring arms 25 on the edge of cap 19 which engage the walls of the recess 9 to frictionally lock the fuse cartridge in such recess.

In the side of the member 14 we preferably cut away a part of said member between the caps 19 and 20 to a depth deeper than the groove 15 so that there is an air space 26 around the fuse wire 21 between said caps.

It will be apparent that when the fuse wire is burnt out in use, upon unscrewing the plug 8 from the socket 5 the fuse cartridge may be easily slipped out of the recess 9 and the caps 19 and 20 removed from the member 14 and a new piece of fuse wire, taken from a spool or however it may be sold on the market, inserted in the recess 18 and groove 15 as before described and the caps 19 and 20 put back on the ends of member 14, the fuse plug inserted in the recess 9 again and the plug adjusted back in the receptacle 5.

We claim:

1. In combination, a fuse plug having a recess extending in one end thereof; a conductor on the outer side of said fuse plug having a portion extending into said recess at the inner end of the latter; a fuse cartridge in said recess and made up of an electrical non-conducting member with a fuse wire extending along one side of said member and a cap on each end of said member in electrical connection with said fuse wire; and a resilient arm attached to the fuse cartridge, disposed between said caps and frictionally engaging the side of said recess.

2. In combination, a fuse plug having a recess extending in one end thereof; a conductor on the outer side of said fuse plug having a portion extending into said recess at the inner end of the latter; a fuse cartridge in said recess and made up of an electrical non-conducting member with a fuse wire extending along one side of said member and a cap on each end of said member and having electrical connection with said fuse wire; and resilient arms on one of said

caps engaging the sides of said recess locking the fuse cartridge in said recess.

3. In combination, a fuse plug body having a recess therein; an electrical conductor having a portion disposed at the inner end of said recess; a fuse cartridge member disposed in said recess; a fuse wire in said cartridge member; a cap on each end of said cartridge member in electrical connection with said fuse wire, one of said caps being in engagement with said electrical conductor and the other of said caps extending slightly from said recess; and spring arms on the cap which extends from said recess, said arms engaging the sides of said recess and holding the cartridge member, fuse wire and caps in said recess.

4. In combination a fuse cartridge comprising an elongated electrical non-conducting member having a groove extending across one end, along one side and to the middle of the other end of said member, there being a recess extending longitudinally in the last-mentioned end of said member at the end of said groove in such end; a fuse wire having one end extending into said recess and its other part lying in said groove; and caps on the ends of said member clamping the fuse wire to the end portions of such member.

5. In combination, a fuse cartridge comprising an elongated electrical non-conducting member having a groove extending across one end, along one side and to the middle of the other end of said member, there being a recess extending longitudinally in the last-mentioned end of said member at the end of said groove in such end; a fuse wire having one end extending into said recess and its other part lying in said groove; and caps on the ends of said member clamping the fuse wire to the end portions of said member, there being a recess in the side of said member between said caps deeper than said groove providing an air space around the portion of the fuse wire between said caps.

6. In combination, a fuse plug body having a recess therein; a fuse cartridge member disposed in said recess; a fuse wire in said fuse cartridge member; a cap on each end of said fuse cartridge member in electrical connection with said fuse wire; and resilient arms on one of said caps engaging the sides of said recess and locking said fuse cartridge member, fuse wire and caps in the recess of said body.

In testimony whereof we have signed our names to this specification on this 30th day of April, A. D. 1918.

CHARLES DAWSON.
EDWARD E. MORGAN.
